UNITED STATES PATENT OFFICE.

NATHAN HARPER, OF NEWARK, NEW JERSEY, ASSIGNOR TO MARCUS W. ADAMS, OF SAME PLACE.

HAT-SIZING APPARATUS.

SPECIFICATION forming part of Letters Patent No. 278,333, dated May 29, 1883.

Application filed August 28, 1882. (No model.)

To all whom it may concern:

Be it known that I, NATHAN HARPER, a citizen of the United States, residing at Newark, in the county of Essex and State of New Jersey, have invented certain new and useful Improvement in Hat-Sizing Apparatus; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to improve and facilitate the sizing or felting of hat-bodies and other fabrics by means of improved felting-surfaces or combinations of surfaces, and of other devices and arrangements operating in connection therewith, as will be herein-after set forth and embodied in the claims.

One prominent feature embraced in the invention consists in the construction and arrangement of various felting-surfaces having concaved or centrally-recessed profiles adapted to allow the hat-bodies, while felting, to traverse or pass over said surfaces in a line at or nearly at right angles to said concaved or centrally-recessed profiles.

Felting-rollers having concave or centrally-recessed longitudinal profiles have already been used in a number of hat-sizing machines; but the employment of such rollers has been confined to what are known to the trade as "three-roller" or "four-roller" machines, in which a single roll of hats is caused to rotate on its own axis within the recess formed between said rollers and parallel with their axes, but having no progressive movement at right angles to said concave profiles. As thus used, the said machines, whether containing three or more rollers, are arranged to form a simple cavity or pocket adapted to hold but one hat-roll at a time, the said cavity being somewhat less in breadth and depth than the diameter of the said hat-rolls. In this class of machines there is therefore no felting-chamber or felting-surface extending at right angles to the axes of the felting-rollers or permitting the hat-rolls, while felting, to traverse or pass over said

rollers in a line at right angles thereto. In my invention the said concave or centrally-recessed surfaces are not confined to concave rollers, but embrace a number of other concave felting elements, which elements, including the rollers, are arranged so as to allow a number of hat-rolls to be under the operation of the felting-surface at the same time, and to impart to said hat-rolls not only a rotating motion on their own axes parallel with said concave profiles, but also a progressive or traveling motion in a line at right angles to the axes of said hat-rolls. The special advantages heretofore obtained from the concave felting-rollers in retarding or preventing the elongation of one hat-roll, and thereby hastening the felting process, is by my improvement extended to a number of additional elements and made to operate on a number of hat-rolls at the same time, thereby largely increasing the capacity of the machine using this form of surface, while the additional variety of motions imparted to the felting fabric by this and other arrangements and combinations hereinafter set forth produces a superior quality of goods.

The invention therefore consists, further, in other arrangements and combinations of parts, all of which will be herein fully described, and finally embodied in the claims.

Referring to the accompanying drawings, in which similar letters of reference indicate like parts in each of the several figures, Figure 1 is a plan of one form of a machine in which my improvements may be used, the upper pressing-rolls being removed to show an interior drum co-operating with the pressing-rolls to felt the hats. Fig. 2 is a side elevation, illustrating more especially the operative arrangement of the several gear-wheels and pulleys. Fig. 3 is a sectional view taken through line *x*, Fig. 1, illustrating more especially the arrangement of the felting-surfaces and the operation of a feeding and discharging device, but showing a straight instead of a concave drum. Figs. 4, 5, 9, 17, 18, and 19 illustrate modified and improved forms of the before-mentioned felting-drum. Figs. 6, 7, 8, and 15 illustrate various forms of pressing-rolls. Figs. 10 and 11 illustrate two forms of

pressing-slats. Figs. 12 and 13 illustrate detached bearings for said pressing rolls and slats. Fig. 14 illustrates the relation of a felting-drum with rolls co-operating therewith, by which a centrally-enlarged chamber is formed. Fig. 16 illustrates in section centrally-recessed or concaved drums and pressing-rolls, so arranged in combination as to produce a centrally-enlarged chamber through which the hat-rolls may travel at right angles to said rolls and drums. Fig. 20 illustrates the combination, with a centrally-concaved drum, of surrounding pressing-rolls having variously-formed peripheries.

In said drawings, A represents a tank for holding water or other felting-liquid, which liquid may be heated by any of the ordinary means, said tank also serving as the bed or foundation of the machine.

B B are the side disks, secured to the interior sides of the tank. I prefer to construct the side disks as illustrated in Figs. 1 and 3, in which B represents the disk secured to the sides of the tank, and B' detachable bearing plates or guides arranged upon and secured to the inner side of the said disks. Said detachable plates are slotted to receive the journals or bearing ends of the rolls b and slats b', said slots being either open, as a, or closed, as a', both methods, however, being usually employed in the same machine to facilitate the adjustment of the pressing rollers or slats. It will be understood that a portion of the disks B lies beneath the surface of the felting-liquid, which being kept hot softens the wood very materially. As heretofore made the disks themselves were slotted to form the bearings for the rollers or slats, and the motion of said rollers or slats wore away the bearings below the surface of the liquid with great comparative rapidity, while the upper or unsubmerged portions of the disks remained unaffected. As thus constructed there was no opportunity for changing the adjustment of said bearings or for removing and renewing the worn portions. By making the slotted plates in detachable sections they can be readily adjusted or readjusted to any line or curve desired and the worn portions removed and replaced without removing or disturbing the remaining portions, thereby adding greatly to the convenience of adjustment and saving largely on the expense entailed by the previous practice of throwing aside the whole disk when a portion of the bearings became defective. These slotted bearings or guides may be made of wood, metal, or any other suitable material, and the form thereof varied and adapted to the style of the machine and the elements employed. Figs. 3, 12, and 13 show three varieties of the detachable plates. It will be understood that the whole of these detachable bearings or guides may be made in a single piece; but the sectional form is the most desirable. Within the aforesaid slotted bearings are arranged around the central felting-

drum D the co-operating felting-rollers b or felting-slats b', an annular chamber being thereby formed between the drum and the series of rollers or slats, through which chamber the hat-rolls pass in the process of felting, as shown in Figs 3 and 20. Said rollers or slats may be fixed at a definite distance from the opposite felting-surface or be left free to move toward or from said surface. The difference between the said rollers b and the slats b' is that the former revolve when acted upon by the hat-rolls and the latter do not. The said slats therefore offer greater resistance to the passage of the hat-rolls than the rollers, and on this account the slats may in some cases be advantageously used in alternation with or instead of the rollers. The working-surface of both may be constructed alike—plain or ribbed, straight or centrally receding. I however prefer to construct the felting-surface with concave or centrally-receding longitudinal profiles, shown in the several Figs. 4, 8, 9, 14, 15, (Nos. 7 and 8,) and 16, whereby the felting-chamber thus formed will possess greater depth or space at or near its center, as shown at q, Fig. 4, than at or near its sides or edges, as at r r, Fig. 14. A felting-chamber having the same special characteristics will likewise be produced if only one of its sides is formed with a concaved or centrally-recessed surface and the other or co-operating surface is formed straight or even slightly convex, as shown at q', Fig. 14. It will be obvious that the extension of such a chamber in a direction transverse to the said concaved profile or profiles of its felting-surface may be continued to any degree by simply increasing the area or number of felting-surfaces in the said transverse direction, thereby enabling three, four, or more hat-rolls to undergo the felting process in said chamber at one time. In constructing said chamber it is not necessary that the centrally-recessed profiles of the felting-surfaces should be confined to the concave or to any other specific form. Almost any form of recessed profile which, when viewed in the direction of the axes of the hat-rolls, recedes at or near the center and advances to greater fullness toward the ends or edges, will, in a degree, accomplish the desired purpose. Figs. 4, 10, and 11 show three varieties of such centrally-recessed profiles, and others may be used, if desired.

Felting-slats having concave or centrally-recessed profiles have heretofore only been used as ribs or projections secured to the surfaces of revolving felting drums, rollers, or belts, and as thus used I do not claim them; but as here used by me the said concave slats form a co-operating felting bed or surface detached and separate from said revolving felting drums, rollers, or slats.

I do not wish to be understood as confining myself, in the use of the centrally-recessed felting-surface, to the annular form of chamber shown in Fig. 3, as said chamber may be likewise constructed in straight lines, as at s,

Fig. 16, or in any other form that the variety of the machine to which they are applied may require.

It will of course be understood that the hats to be felted are inclosed, three or four at a time, in the usual wrappers and made up into cylindrical or elongated rolls, the rolls being fed to the machine with their axes parallel to the axes of the revolving felting surface or surfaces of the mechanism.

The felting drums or rollers may be plain, as in Figs. 3, 4, and 8, or be ribbed, corrugated, or grooved in lines parallel, or nearly so, with their axis, as in Figs. 5 and 6, Sheet 1, also Sheet 2, Fig. 15, Nos. 1 and 3; or they may be ribbed, corrugated, or grooved crosswise of their axis, either spirally, as No. 4, Fig. 15, or at right angles, as in Figs. 7, 15, Nos. 2 and 18. The felting-slats or other elements may likewise be ribbed, fluted, or corrugated in a similar manner, either lengthwise or transversely to their length. The shapes and sizes of the ribs and of the grooves on said felting-surfaces may be varied in any manner, though for general purposes I prefer the curved or rounded forms. The ribs on said surfaces may be formed in continuous lines or be divided into sections, as illustrated in Fig. 15, No. 4.

Instead of being ribbed or corrugated, the felting-surfaces may be embossed or be provided with protuberances of any shape desired, as Fig. 15, No. 5. The ribs or other projecting elements constitute the main working parts of said felting-surfaces, and are applicable alike to straight forms and to those centrally recessed, as Fig. 15, Nos. 7 and 8. In the latter case the ribs or projections may form the said recessed profile, as Fig. 15, No. 7; or the recess may be formed independently of said ribs or projections, and the ribs or projections made to conform thereto, as Fig. 15, No. 8. Each variety of these felting-surfaces has a specific and characteristic effect on the felting fabric, and by the combination of two or more of said varieties in one machine results can be obtained which are unattainable from either form when employed alone. In combining these different felting-surfaces, if one of said surfaces is plain, as D, Figs. 3 and 4, I prefer to construct the co-operating felting-surface with elements part of which are ribbed or corrugated lengthwise or the others crosswise, alternating with each other, as 1 and 2, 3 and 6, Fig. 16, or by placing several of one variety in succession, followed by several of another variety, as Fig. 20. If one of the surfaces is ribbed or corrugated lengthwise, as Fig. 5, I then prefer to employ for the co-operating surface elements that are ribbed or corrugated crosswise, as Fig. 7, also Nos. 2 and 6, Fig. 15, and vice versa. By these combinations the lines of pressure of the different felting-surfaces are made to continually intersect each other on the bodies of the hat-rolls, which are thereby subjected to a

constantly-changing series of alternating motions in each direction and over every part of their surfaces. In this manner, even without the use of the concave or centrally-receding surfaces, I am able to effect a saving of time and to produce a very superior quality of felt, and by the addition of said centrally-receding forms the saving of time is still further increased.

The various felting-surfaces hereinbefore described may be constructed of metal, hard rubber, wood, or any other substance of a suitably-rigid nature, said rigid surfaces being, as herein arranged, well adapted to the felting of the larger portion of the hats manufactured; but in order to adapt the invention more completely to the finest grades of goods, I have also provided a somewhat softer felting-surface, consisting of a jacket or belt composed preferably of india-rubber, although any other suitable yielding material may be used as a substitute. Said jacket or belt may, like the other felting-surfaces, be provided with ribs or corrugations running either lengthwise or crosswise thereof, thereby enabling it to enter into similar combinations with the co-operating surface as those already described, and to produce the same movements on the hat-rolls. When secured on a single drum it is herein designated a "jacket." When applied so as to travel over a series of two or more drums it is herein called a "belt." Said jacket or belt may be constructed in different forms and be applied to several varieties of drums: First, it can be constructed with a straight profile and be applied to a drum or series of drums of like form; second, it may be constructed with a centrally-receding profile and be applied to a drum or series of drums having straight profiles, as in Fig. 9; third, it may be constructed with a centrally-receding profile and be applied to a drum of the same form, as in Fig. 19; fourth, it may be constructed with a straight profile and be applied to a drum or series of drums with concave or centrally-receding profiles, as in Fig. 17.

It will be observed that in Figs. 5, 9, and 19 the jackets fit closely on the surfaces of the several drums, and have no inward or outward movement thereon, the purpose of each of said jackets on these drums being not the production of a surface which shall yield so as to change its outline under the pressure of the hat-rolls, but simply to relieve said hat-rolls in the early stages of the felting process from the harshness due to contact with an essentially hard surface, while at the same time they practically furnish for the later stages of the process all the rigidity of surface and outline that would be obtained if said jackets were not employed; but in Figs. 16 and 17 the concave or centrally recessed surface of the drums produces a cavity underneath the straight surface of the jacket or belt, and as there are no springs or other elements employed in said cavity or recess, there is, therefore, nothing to prevent the said jacket or belt from yielding

inwardly under each degree of pressure, thereby constantly conforming its surface to the ever-varying shape of the hat-rolls, and so felting every part of the same. The capacity of this variety of felting-surface to thus yield and conform itself to the particular shape of the hat-rolls gives it a special advantage not possessed by either of the varieties hereinbefore described, or by any surface having a permanent unchanging outline.

I am aware that hat-sizing machines containing a single revolving felting-drum covered with a jacket have been used before; but in such cases the said jacket did not fit closely on the surface of the drum, but was distended or pushed outwardly therefrom by water or spring pressure, so as to form a surface that would yield readily both inwardly and outwardly. As thus constructed I do not use or claim them, the drum and jacket employed by me being entirely different both in construction and operation, as hereinbefore set forth.

Felting-rollers have already been used having ribs or corrugations running lengthwise of their axes, and also rollers with ribs or corrugations running crosswise thereof; but the two varieties have not heretofore, to my knowledge, been combined in one machine.

30 The drum D is actuated, preferably, by the gear-wheel c, which engages with the pinion d, the latter receiving motion from the driving-pulley e.

In connection with the felting-surfaces there is arranged a feeding-belt, f', for carrying the hat-rolls to the felting-surfaces, and a discharging-belt f, for the purpose of removing and carrying the hat-rolls from the felting-surface, the construction and operation of which belts are described in a preceding specification, forming part of my application No. 56,634, and therefore not repeated. In connection with said feeding and discharging belts is here arranged mechanism for automatically imparting to the free or inner end of said discharging-belt f an upward and downward movement toward or from the drum D, as indicated in outline in Fig. 3. This movement is produced by the revolutions of the cam i engaging with the side strips, h, or block h', Figs. 1 and 3, arranged thereon. The cam is actuated by the pulley n, connected with the pulley o upon the drum-shaft. When the hats are in a tender stage one revolution of the hat-rolls around the drum before removal is sufficient, and the cam, during this stage, is therefore left inoperative and the belt f remains on the surface of the drum; but when the felt has gained a degree of hardness two such revolutions before removal are desirable. 60 At this stage power is applied to the cam, and the belt f is thereby raised from the drum and retained in its raised position long enough to allow the hat-rolls to make the said two revolutions before said belt descends to remove them. This periodic raising and falling of the belts is thus continued until the hats are felted.

By these means the hat-rolls are enabled to make the number of revolutions through the felting-chamber that may be required without traveling over the discharging and feeding belts until they are ready for removal, thereby keeping them much hotter than would be possible if they had to traverse said belts at each revolution through the chamber.

Having thus described my invention, what I claim as new, and desire to secure by Letters Patent, is—

1. In a hat-sizing machine, a felting-chamber having more depth or space at or near its center, as at q, than at or near its sides or edges, as at r, said chamber being constructed and adapted to cause the hat-rolls, while felting, to have both a rotary motion on their axes and a progressive motion at right angles thereto, substantially as set forth. 85

2. In a hat-sizing machine, a felting-bed having a concave or centrally-receding profile in the line of the axes of the hat-rolls, said bed being constructed and adapted to cause said hat-rolls, while felting, to have both a rotary motion on their axes and a progressive motion at right angles thereto, substantially as set forth. 90

3. In a hat-sizing machine, one or more drums, pulleys, or rollers having a concave or centrally-receding longitudinal profile and forming one part or side of a felting-chamber, said chamber being constructed and adapted to cause the hat-rolls, while felting, to have both a rotary motion on their axes and a progressive motion at right angles thereto, substantially as set forth. 95

4. In a hat-sizing machine, a twofold series of drums, pulleys, or rollers having concaved or centrally-receding longitudinal profiles and forming the two sides or parts of the two sides of a felting-chamber, said chamber being constructed and adapted to cause the hat-rolls, while felting, to have both a rotary motion on their axes and a progressive motion at right angles thereto, substantially as set forth. 105

5. In a hat-sizing machine, a felting-surface consisting of a series of rollers having a concave or centrally-receding longitudinal profile and free to move inward or outward toward or from the felting-chamber, said rollers and chamber being constructed and adapted to cause the hat-rolls, while felting, to have both a rotary motion on their axes and a progressive motion at right angles thereto, substantially as set forth. 115

6. In a hat-sizing machine, one or more drums, pulleys, or rollers having concave or centrally-receding longitudinal profiles and fluted, ribbed, or corrugated lengthwise of their axes, in combination with a co-operating felting-surface arranged at a suitable distance therefrom to form a felting-chamber, said chamber being adapted to cause the hats, while felting, to have both a rotary motion on their axes and a progressive motion at right angles thereto, substantially as set forth. 125

7. In a hat-sizing machine, one or more drums, pulleys, or rollers having concave or centrally-receding longitudinal profiles and fluted, ribbed, or corrugated crosswise of their axes, in combination with a co-operating felting-surface arranged at a suitable distance therefrom to form a felting-chamber, said chamber being adapted to cause the hats, while felting, to have both a rotary motion on their axes and a progressive motion at right angles thereto, substantially as set forth.
8. In a hat-sizing machine, the combination of one or more felting drums, pulleys, or rollers fluted, ribbed, or corrugated lengthwise of their axes with one or more felting-drums, pulleys, or rollers fluted, ribbed, or corrugated crosswise of their axes.
9. In a hat-sizing machine, a felting-bed consisting of a series of slats having concave or centrally-recessed longitudinal profiles, said slats being employed separate and detached from the felting drums, rollers, or belts used in said machine, and adjusted to form a convex felting-chamber, substantially as set forth.
10. In a hat-sizing machine, a felting-surface consisting of a series of slats having concave or centrally-recessed longitudinal profiles, and mounted by their ends only in slots or guides adapted to allow them to move toward or from the surface of the hat-rolls, substantially as set forth.
11. In a hat-sizing machine, the combination of one or more felting-slats having concave or centrally-recessed longitudinal profiles with one or more felting-rollers having concave or centrally-recessed profiles, the said slats and rollers being mounted by their ends in or between slots or guides adapted to allow them to move toward or from the surface of the hat-rolls, substantially as set forth.
12. In a hat-sizing machine, the combination of a single revolving felting-drum having a rigid felting-surface, a felting-chamber surrounding or partially surrounding said drum, and a series of pressing-rollers forming a co-operating felting-bed on the outer side of said felting-chamber, substantially as set forth.
13. In a hat-sizing machine, a single revolving felting drum or cylinder having a rigid surface, ribbed, corrugated, or fluted either lengthwise or crosswise of its axis, in combination with a co-operating series of felting-rollers, substantially as set forth.
14. In a hat-sizing machine, a single revolving felting drum or cylinder having a rigid surface, in combination with a co-operating series of felting-rollers and felting-slats separated from said drum by the felting-chamber and mounted by their ends in slots or guides adapted to allow them to move inward or outward toward or from the surface of said drum.
15. In a hat-sizing machine, two co-operat-
- ing surfaces or series of surfaces arranged at an appropriate distance apart to form a felting-chamber between them, either or both of said surfaces having a concave or centrally-recessed profile, said surfaces being constructed and adapted to cause the hat-rolls, while felting, to have both a rotary motion on their axes and a progressive motion at right angles thereto, substantially as set forth.
16. In a hat-sizing machine, a felting-belt having a continuous concave or centrally-recessed surface, substantially as set forth.
17. In a hat-sizing machine, a felting jacket or belt having a straight profile, in combination with and applied to one or more drums or rollers having concave profiles, the felting function of said jacket or belt being performed by the outer surface thereof, substantially as set forth.
18. In a hat-sizing machine, a felting belt, apron, or jacket having its surface ribbed, fluted, or corrugated either longitudinally or at right angles to its length, in combination with a series of co-operating felting-rollers, substantially as set forth.
19. In a hat-sizing machine, stationary disks, as B, in combination with detachable slotted bearings or guides, as B', said detachable bearings or guides being secured to said disks and adapted to receive and guide the bearing ends of the pressing-rollers or pressing-slats, substantially as set forth.
20. In a hat-sizing machine, mechanism adapted to automatically raise and lower the inner end of the discharging-belt to enable the hat-rolls to pass by said belt or to pass onto the same, as may be desired, substantially as set forth.
21. In a hat-sizing machine, a cam or eccentric arranged to automatically raise and lower the inner end of the discharging mechanism or belt, substantially as herein set forth.
22. In a hat-sizing machine, the combination of a single revolving felting-drum, an annular felting-chamber, co-operating felting-rollers, a feeding and a discharging belt, substantially as and for the purpose set forth.
23. In a hat-sizing machine, the combination of a single revolving felting-drum provided with a yielding or elastic jacket closely fitting its surface, a felting-chamber surrounding or partially surrounding said drum, and a series of pressing-rollers forming a co-operating felting-bed on the outer side of said chamber, substantially as set forth.

In testimony that I claim the foregoing I have hereunto set my hand this 24th day of May, 1882.

NATHAN HARPER.
